RAILWAY TRAFFIC CONTROLLING APPARATUS

Filed August 20, 1925

UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 20, 1925. Serial No. 51,390.

My invention relates to railway traffic controlling apparatus, and particularly to apparatus of the type comprising train carried governing mechanism controlled in accordance with traffic conditions in advance.

I will describe one form of railway traffic controlling apparatus embodying my invention, and will then point out the novel features thereof in claims.

10 The accompanying drawing is a view, partly diagrammatic, illustrating the train carried portion of one form of railway traffic controlling apparatus embodying my invention.

15 Referring to this drawing the reference character L designates a brake application valve which is arranged to control the train brakes. This valve comprises a casing which is divided into a slide valve chamber

20 3 and a piston chamber 2, the latter containing a reciprocable piston 4. The piston 4 is constantly urged to the right by a spring 5. The slide valve chamber 3 is at all times supplied with fluid pressure

25 through pipe 7 from a suitable source not shown in the drawing. A pipe 8 communicates with chamber 2. When this pipe is connected with atmosphere, as will be explained hereinafter, the pressure in chamber 3 moves piston 4 to the left against the force exerted by a spring 5. Piston 4 is provided with a restricted orifice 4^a and when pipe 8 is closed, pressure leaking through this orifice 4^a from chamber 3 gradually builds up a pressure in chamber 2. When the pressures in chambers 2 and 3

30 are approximately equal the combined force of the pressure exerted on the left hand side of piston 4 and the pressure exerted by spring 5 moves piston 4 to the right. Piston 4 controls a slide valve 6 so that when the piston is in its left hand position pipe 9 is connected with atmosphere through ports 10 and 11, but when the piston is in its right hand position pipe 9 is blanked by slide valve 6. Pipe 9 is normally supplied with fluid pressure and controls brake applying apparatus in such manner that when the pressure in this pipe is reduced the

40 brakes on the train are automatically applied.

Pipe 8 is controlled by a repeater valve J which comprises a chamber 12 contain-

ing a flexible diaphragm 13. The diaphragm 13 controls a plunger 14 carrying a pin valve 16. The plunger 14 is constantly urged upwardly by a spring 15. When atmospheric pressure exists in chamber 12 plunger 14 moves to the upper position under the influence of spring 15 and pin valve 16 then connects chamber 17 with pipe 19. When chamber 12 is supplied with fluid pressure diaphragm 13 is moved downwardly, thereby forcing plunger 14 and pin valve 16 to their lower positions under which conditions pipe 19 is disconnected from chamber 17 and is connected with atmosphere through port 18. Pipe 19 is normally connected, through a suppressing valve M, with a stop reservoir 37. Chamber 17 of repeater valve J is constantly connected with the piston chamber 2 of application valve L by means of pipe 8.

The pressure in chamber 12 of valve J is controlled by a relay valve H comprising a plunger 77 carrying an armature 22 which is acted upon by a winding 27. The plunger 77 controls a pin valve 22 which is normally urged upwardly by a spring 23. When winding 27 is de-energized spring 23 moves pin valve 22 and plunger 77 to their upper positions, and chamber 12 of valve J is then connected with atmosphere through pipe 20 and port 24 of valve H. A timing reservoir 21 is constantly connected with pipe 20. When winding 27 of valve H becomes energized armature 22^a is drawn downwardly, moving plunger 77 and pin valve 22 to their lower positions thereby disconnecting pipe 20 from port 24 and connecting this pipe with chamber 26. Chamber 26 is constantly supplied with fluid pressure through pipe 25 from a source of energy not shown in the drawing.

The suppressing valve M comprises a chamber 28 provided with a flexible diaphragm 29. This diaphragm controls a plunger 30 carrying a piston 31 and a pin valve 32. A spring 33 normally urges the plunger 30 downwardly. When atmospheric pressure exists in chamber 28 the plunger 30, carrying valve 32 and piston 31, occupies its lower position. Under these conditions pipe 19 is connected with pipe 36, and valve 32 blanks chamber 35. Chamber 35 is constantly supplied with fluid pres-

sure through pipe 34 from a source not shown in the drawing.

The pressure in chamber 28 of valve M is controlled by acknowledging valve K. This valve normally occupies the position illustrated in the drawing in which an acknowledging reservoir 40 is connected with a source of fluid pressure not shown in the drawing, through pipe 39, valve K and pipe

38. When handle K¹ of acknowledging valve K is operated, the acknowledging reservoir 40 is disconnected from pipe 39 and is connected with pipe 41. If the application valve L is in the normal position in

which it is illustrated in the drawing, fluid pressure then flows from reservoir 40, through pipe 38, acknowledging valve K, pipe 41, port 42 of application valve L and pipe 43, to chamber 28 of suppressing valve

M. This pressure moves diaphragm 29 upwardly, lifting piston 31 to blank pipe 19. At the same time valve 32 opens and fluid pressure is supplied from chamber 35, through pipe 36 to stop reservoir 37. The

pressure supplied to chamber 28 of the suppressing valve M from the acknowledging reservoir 40 is gradually dissipated to atmosphere through a restricted port 78, so that after the expiration of a time interval

the spring 33 returns plunger 30 to its lower position, disconnecting chamber 35 from stop reservoir 37 and again establishing communication between pipe 36 and pipe 19.

The reference character D designates a pneumatic circuit controller which comprises a chamber 45 provided with a flexible diaphragm 47. The diaphragm 47 controls a plunger 48 which is constantly urged downwardly by a spring 46. Chamber 45 of circuit controller D is constantly connected with stop reservoir 37 by a pipe 44. The plunger 48 of circuit controller D is operatively connected with two contact fingers

62 and 49. When atmospheric pressure exists in reservoir 37, plunger 48 of circuit controller D occupies its lower position and contacts 62 and 49-49^b are closed. When reservoir 37 is charged with fluid pressure

plunger 48 of circuit controller D is moved upwardly against the force exerted by spring 46 so that contact 49-49^a is closed but contacts 62 and 49-49^b are open.

The reference character A designates a relay which, for purposes of explanation, I will call a "main" relay. This relay is controlled in accordance with traffic conditions in advance by means which form no part of my present invention and which I have

omitted from the drawing for the sake of simplicity. For present purposes it is sufficient to state that the relay A is energized in the normal direction, so that contacts 55 and 56 are swung to the right, under safe

or proceed traffic conditions; that the relay

is energized in the reverse direction, so that contacts 55 and 56 are swung to the left, under caution traffic conditions; and that relay A is de-energized, so that contacts 55 and 56 occupy intermediate positions, under stop or dangerous traffic conditions.

A stick relay G is controlled by relay A and circuit controller D so that when relay A becomes energized in the reverse direction relay G becomes energized provided circuit controller D is actuated by fluid pressure from stop reservoir 37, and relay G subsequently remains in its energized condition as long as relay A is energized in the reverse direction. The pick-up circuit for relay G may be traced from one terminal B of a source of energy not shown in the drawing, through reverse contact 55-55^b of relay A, wires 64 and 65, contact 49-49^a of circuit controller D, wire 67, winding of relay G and wire 68 back to terminal C, of the same source. When the circuit just traced is closed relay G becomes energized and a stick circuit is then completed for this relay passing from terminal B through reverse contact 55-55^b of relay A, wires 64, 69 and 70, front contact 71 of relay G, wire 72, winding of relay G, and wire 68 back to terminal C.

Winding 27 of valve H is controlled by relay A and by relay G. One circuit for this winding passes from terminal B, through normal contact 55-55^a of relay A, wires 57 and 58, back contact 59 of relay G, wire 60, and winding 27 of valve H to terminal C. This circuit is closed only when relay A is energized in the normal direction and relay G is de-energized. If relay A is energized in the reverse direction and relay G is also energized another circuit is closed for winding 27 of valve H from terminal B through reverse contact 55-55^b of relay A, wires 64, 69 and 73, front contact 59 of relay G, wire 60, and winding 27 of valve H to terminal C.

The condition of the apparatus is indicated to the engineman by means of three signals here shown as electric lamps 50, 51 and 52. Lamp 50, which I will call the "proceed" lamp, is provided with a circuit

passing from terminal B, through normal contact 55-55^a of relay A, wires 57 and 61, contact 62 of circuit controller D, wire 63 and lamp 50 to terminal C. The proceed lamp 50 therefore is lighted only when stop reservoir 37 is connected with atmosphere and when relay A is energized in the normal direction.

When relay A is energized in the reverse direction and stop reservoir 37 is connected with atmosphere, current flows from terminal B, through reverse contact 55-55^b of relay A, wires 64 and 65, contact 49-49^b of circuit controller D, wire 66 and caution lamp 51 to terminal C. When

relay A is de-energized the stop lamp 52

is lighted only when stop reservoir 37 is connected with atmosphere, current flows from terminal B, through reverse contact 55-55^b of relay A, wires 64 and 65, contact 49-49^a of circuit controller D, wire 66 and caution lamp 51 to terminal C. When

relay A is de-energized the stop lamp 52

is lighted, the circuit for this lamp passing from terminal B', back contact 56 of relay A, wire 74, and lamp 52 to terminal C'.

As shown in the drawing, relay A is energized in the normal direction, corresponding to proceed conditions of traffic in advance. Both circuits for relay G are therefore open at contact 55-55^b of relay A and consequently relay G is de-energized. Winding 27 of valve H is energized over back contact 59 of relay G and normal contact 55-55^a of relay A. Pipe 20 is therefore disconnected from port 24 and is connected with chamber 26. Fluid pressure is therefore supplied to timing reservoir 21 and to chamber 12 of repeater valve J. Pin valve 16 of valve J occupies its normal or lower position and so pipe 19 is connected with atmosphere through port 18. Chamber 17 of valve J is blanked by valve 16 and pressure supplied to chamber 2 of valve L through orifice 4^a charges this chamber to the same pressure as chamber 3. As a result piston 4 occupies its right hand position and pipe 9 is blanked by slide valve 6 so that the brakes are not applied automatically. The acknowledging valve K is in its normal position, that is, acknowledging reservoir 40 is charged with fluid pressure from pipe 39. Chamber 28 of suppressing valve M is connected with atmosphere through port 78 so that plunger 30 of valve M is in its lower position. Stop reservoir 37 is therefore connected with atmosphere through pipe 36, valve M, pipe 19 and port 18 of valve J. Valve 32 of the suppressing valve M is of course closed. Stop reservoir 37 being connected with atmosphere, atmospheric pressure also exists in chamber 45 of circuit controller D, so that plunger 48 of this circuit controller occupies its lower position. Contact 62 is therefore closed and lamp 50 is lighted to indicate proceed.

In explaining the operation of the apparatus I will first assume that relay A becomes energized in the reverse direction as by the entrance of the train into a stretch of track in which caution traffic conditions are imposed. I will also assume that the engineman does not acknowledge the change in traffic conditions by proper manipulation of valve K. The reversal of relay A closes contact 55-55^b but the pick-up circuit for relay G is open at contact 49-49^a of circuit controller D. Relay G therefore remains in its de-energized condition. One circuit for winding 27 of valve H is now open at normal contact 55-55^a of relay A, and the other circuit for this winding is open at front contact 59 of relay G. Winding 27 therefore becomes de-energized, allowing spring 23 to move pin valve 22 to its upper position. As a result, pipe 20 is disconnected from chamber 26 and is connected with atmosphere through port 24. The

pressure in timing reservoir 21 and chamber 12 of valve J is gradually dissipated to atmosphere through port 24. After the expiration of a time interval spring 15 overcomes the reduced pressure in chamber 12 and lifts pin valve 16 to its upper position. Piston chamber 2 of application valve L is then connected through pipe 8, valve J, pipe 19, valve M and pipe 36, with the stop reservoir 37. As a result of this connection the pressure in piston chamber 2 of the application valve L is reduced and the pressure in chamber 3 of this valve forces piston 4 to the left and connects pipe 9 with atmosphere through port 10 in slide valve 6 and port 11. The consequent reduction in the fluid pressure in pipe 9 causes an automatic application of the brakes.

If the engineman takes proper steps, however, he may prevent an automatic application of the brakes upon a change from proceed to caution traffic conditions. To explain this, I will assume that the train is operating under proceed traffic conditions and that all parts of the apparatus are in the positions illustrated in the drawing, as hereinbefore explained. If relay A now becomes energized in the reverse direction the engineman may prevent an automatic application of the brakes by operating the acknowledging valve K. The operation of the acknowledging valve may take place either immediately before the reversal of relay A or after the reversal of this relay and prior to the expiration of the time interval required for repeater valve J to operate following de-energization of valve H. When the engineman operates valve K the pressure in acknowledging reservoir 40 is supplied to chamber 28 of the suppressing valve M as has already been described. The pressure so supplied to chamber 28 moves plunger 30 upwardly and blanks pipe 19. This movement of plunger 30 also opens valve 32 and supplies fluid pressure from chamber 35 through pipe 36 to stop reservoir 37 thereby charging this reservoir with fluid pressure. After the expiration of the time required for the fluid pressure thus supplied to chamber 28 to be dissipated to atmosphere through port 78, valve M returns to its initial condition thereby again connecting pipe 19 with pipe 36.

As long as reservoir 37 is charged with fluid pressure, contact 49-49^a is closed when reverse contact 55-55^b of relay A closes, therefore, the pick up circuit for relay G is completed and this relay becomes energized. The closing of front contact 71 of relay G completes its stick circuit and the relay therefore remains in its energized condition as long as relay A is energized in the reverse direction. The closing of front contact 59 of relay G completes the circuit for

winding 27 of valve H including reverse contact 55—55^b of relay A. When valve M returns to its initial position, the pressure in stop reservoir 37 is discharged to atmosphere through port 18 of valve J, and circuit controller D again opens but relay G is now maintained in its energized condition independently of contact 49—49^a of circuit controller D and therefore an automatic application of the brakes is prevented by the continuous energization of winding 27 of valve H. When circuit controller D returns to its normal position the closing of contact 49—49^b thereon completes the circuit for the lamp 51 which becomes lighted to indicate caution. It should be pointed out that upon a change from proceed to caution traffic conditions the caution lamp 51 becomes lighted immediately if the engineman does not acknowledge this change in traffic conditions. If however, the engineman does acknowledge, contact 49—49^b is opened, and lamp 51 is extinguished until after the stop reservoir has been discharged to atmosphere following the acknowledgment.

I will assume that the train is proceeding under caution traffic conditions with relay G energized, and that relay A becomes de-energized as by a change from caution to stop traffic conditions. The closing of back contact 56 of relay A immediately closes the circuit for lamp 52, which indicates stop. The opening of reverse contact 55—55^b of relay A breaks the stick circuit for relay G. Due to the slow acting characteristics of this relay, a time interval elapses before front contact 71 of the relay opens. This time interval is sufficient to bridge a brief opening of contact 55—55^b due, for example to mechanical vibration. The opening of contact 55—55^b also interrupts one circuit for winding 27 of valve H. The other circuit for winding 27 is open at normal contact 55—55^a of relay A and winding 27 therefore becomes de-energized. The consequent operation of valve H connects pipe 20 with port 24 as explained hereinbefore and after the expiration of a time interval repeater valve J is operated to lift pin valve 16. If the change from caution to stop traffic conditions is not acknowledged by proper operation of valve K this operation of valve J will cause the reversal of the application valve L by connecting chamber 2 with stop reservoir 37. If, however, prior to the operation of valve J the engineman has operated valve K, piston 31 and valve 32 of suppressing valve M will be lifted, as explained hereinbefore, and stop reservoir 37 will then be charged with fluid pressure. As long as piston 31 of the suppressing valve M occupies its upper position pipe 19 is blanked. It is manifest therefore that if the engineman operates the acknowledging valve K before repeater valve J operates, the lifting of pin valve 16

of valve J cannot connect chamber 2 of the application valve L with the stop reservoir until valve M returns to its initial position. When this happens, that is, when the pressure in chamber 28 of suppressing valve M has been sufficiently reduced by dissipation to atmosphere through port 78 to permit spring 33 to move plunger 30 carrying piston 31 and valve 32 downwardly, stop reservoir 37 is connected with pipe 19. Valve 16 of repeater valve J is in its upper position however and when valve M reverses chamber 2 of application valve L is connected directly with the stop reservoir 37. The stop reservoir has been previously charged with fluid pressure from chamber 35, however, and therefore when chamber 2 of valve L is connected with this reservoir there is no resulting reduction in the pressure in chamber 2. The application valve L therefore does not reverse and the brakes are not applied. It will be noted that under these conditions, as soon as reservoir 37 is charged with fluid pressure, circuit controller D is also supplied with such pressure and that contact 49—49^a is closed.

When the train is proceeding under stop traffic conditions relays A and G are both de-energized, relay valve H is de-energized, and valve J is in its upper position. Valve M is in its normal position and application valve L is in its normal position, although chamber 2 of valve L is connected through repeater valve J and suppressing valve M with the stop reservoir 37. If, under these conditions, relay A becomes energized in the reverse direction as by a change from stop to caution traffic conditions, the pick up circuit for relay G is immediately closed over contact 49—49^a of circuit controller D, now closed. Relay G therefore picks up, closing its stick circuit at its own front contact 71 and completing the circuit for winding 27 of valve H at front contact 59. Pin valve 22 of valve H therefore is moved downwardly and fluid pressure is supplied from chamber 26 of valve H to timing reservoir 21 and to chamber 12 of valve J. Pin valve 16 of valve J therefore moves downwardly to disconnect chamber 2 of valve L from the stop reservoir. This motion of pin valve 16 connects the stop reservoir with atmosphere through port 18 of valve J. The pressure in stop reservoir 37 is therefore dissipated to atmosphere and circuit controller D returns to its normal position so that caution lamp 51 becomes lighted over contact 49—49^b to indicate that the apparatus has returned to the normal condition corresponding to caution traffic conditions. It should be particularly pointed out that upon a change from stop to caution traffic conditions no acknowledgment on the part of the engineman is necessary to prevent an automatic application of the brakes.

Should relay A become energized in the normal direction, the opening of contact 55-55^b interrupts the stick circuit for relay G and this relay becomes de-energized. The closing of back contact 59 thereon completes a circuit for winding 27 of valve H including normal contact 55-55^a of relay A and therefore this change in the condition of relay A does not affect any of the apparatus controlled by valve H. Due to the slow releasing characteristics of relay G, a time interval may elapse after the opening of front contact 59 and before the closing of the circuit for winding 27 of valve H over back contact 59. The timing reservoir 21 requires a longer time interval to discharge through port 24 of valve H, and therefore valve J does not have time to operate. Contact 62 of circuit controller D being closed, lamp 50 becomes lighted to indicate that the apparatus is now in the condition corresponding to proceed traffic conditions. It will be noted that no acknowledgment is necessary to prevent an automatic application of the brakes upon a change from caution to proceed traffic condition.

It will therefore be seen that my invention comprises a single relay valve provided with one circuit which is closed at all times under proceed traffic conditions. Upon a change from proceed to caution traffic conditions a second circuit is closed for the valve provided only that such change is acknowledged by suitable action on the part of the engineman. Under stop traffic conditions this valve is invariably de-energized. Upon any change from more restrictive to less restrictive traffic conditions, however, the circuit corresponding to such less restrictive condition is closed independently of such acknowledgment.

One feature of my invention is the provision in apparatus for controlling such relay valve, of contacts responsive to the pressure in the stop reservoir, and a stick relay controlled in part by these contacts.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, automatic brake applying apparatus, a reservoir normally connected with atmosphere, means for at times supplying said reservoir with fluid pressure, a first valve comprising a chamber normally supplied with fluid pressure, a relay valve comprising a winding, means controlled by said relay valve and effective when said winding is deenergized to connect said chamber with said reservoir, means controlled by said first valve and effective when the pressure in said chamber is reduced to cause operation of said automatic apparatus, a contact responsive to the pressure in said reservoir, a relay controlled by said contact, and means controlled by said relay for energizing said winding.

2. Railway traffic controlling apparatus comprising a train carried reservoir normally connected with atmosphere, manually operable means for at times supplying said reservoir with fluid pressure, a contact responsive to the pressure in said reservoir, a relay controlled in part by said contact, and brake applying apparatus on the train set into operation when said relay becomes deenergized unless said reservoir is charged. 70

2. Railway traffic controlling apparatus comprising a train carried reservoir normally connected with atmosphere, manually operable means for at times supplying said reservoir with fluid pressure, a contact responsive to the pressure in said reservoir, a relay controlled in part by said contact, and brake applying apparatus on the train set into operation when said relay becomes deenergized unless said reservoir is charged. 75

3. Railway traffic controlling apparatus comprising a train carried reservoir normally connected with atmosphere, manually operable means for at times supplying said reservoir with fluid pressure, a contact responsive to the pressure in said reservoir, a relay, a pick up circuit for said relay controlled by said contact and responsive to traffic conditions, a stick circuit for said relay including a branch around said contact, and brake applying apparatus on the train set into operation when said relay is deenergized unless said reservoir is charged. 85

4. Railway traffic controlling apparatus comprising a main relay on a train responsive to traffic conditions, a reservoir normally connected with atmosphere, means for at times supplying said reservoir with fluid pressure, a contact responsive to the pressure in said reservoir, a stick relay controlled by said main relay and by said contact, and automatic brake applying apparatus on the train set into operation when said relay is deenergized unless said reservoir is charged. 100

5. Railway traffic controlling apparatus comprising a reservoir on a train normally connected with atmosphere, means for at times supplying said reservoir with fluid pressure, a relay, a pick up circuit for said relay controlled in accordance with the pressure in said reservoir, a stick circuit for said relay controlled only by traffic conditions, and automatic brake applying apparatus set into operation when said relay is deenergized unless said reservoir is charged. 110

6. Railway traffic controlling apparatus comprising a reservoir on a train normally connected with atmosphere, means for at times supplying said reservoir with fluid pressure, a contact responsive to the pressure in said reservoir, automatic brake applying apparatus controlled in accordance with the pressure in said reservoir, and means controlled by said contact for actuating said brake applying apparatus. 125

7. Railway traffic controlling apparatus comprising a reservoir on a train normally connected with atmosphere, means for at times charging said reservoir with fluid pressure, a contact responsive to the pressure in said reservoir, a brake application valve comprising a chamber normally supplied with fluid pressure and arranged to apply the brakes when the pressure in said chamber is reduced, and means controlled in part by said contact for at times connecting said chamber with said reservoir. 55
8. Railway traffic controlling apparatus comprising a reservoir on a train normally connected with atmosphere, means for at times charging said reservoir with fluid pressure, a contact responsive to the pressure in said reservoir, a brake application valve comprising a chamber normally supplied with fluid pressure and arranged to apply the brakes when the pressure in said chamber is reduced, a valve arranged when opened to connect said chamber with said reservoir, means effective under proceed traffic conditions to hold said valve closed, and means effective upon a change from proceed to caution traffic conditions to hold said valve closed provided said contact is operated by pressure from said reservoir. 60
9. Railway traffic controlling apparatus comprising a train carried relay arranged to be energized in the normal or the reverse direction or to be deenergized depending upon traffic conditions in advance, a valve, a reservoir, automatic brake applying apparatus controlled by said valve and controlled in accordance with the pressure in said reservoir, a contact responsive to the pressure in said reservoir, means for closing said valve when said relay is energized in the normal direction, and other means including said contact for closing the valve when said relay is energized in the reverse direction, the valve being open when said relay is deenergized. 65
10. Railway traffic controlling apparatus comprising a train carried main relay arranged to be energized in the normal or the reverse direction or to be deenergized depending upon traffic conditions in advance, a reservoir normally connected with atmosphere, means for at times charging said reservoir with fluid pressure, a chamber normally supplied with fluid pressure, means for applying the brakes if the pressure in said chamber is reduced, a magnet valve arranged when deenergized to connect said chamber with said reservoir, a normally open contact arranged to be closed when said reservoir is charged with fluid pressure, a stick relay having a pick up circuit including said contact and a reverse contact of said main relay, a stick circuit for said stick relay including its own front contact and a reverse contact of said main relay, a circuit for said magnet valve including a back contact of said stick relay and a normal contact of said main relay, and a second circuit for said magnet valve including a reverse contact of said main relay and a front contact of said stick relay. 70
11. Railway traffic controlling apparatus comprising a train carried magnet valve, means for applying the brakes on the train when the winding of said valve is deenergized, means for energizing the winding of said valve under proceed traffic conditions, and other means for at times energizing said winding under caution traffic conditions, said winding being deenergized under stop traffic conditions. 75
12. Railway traffic controlling apparatus comprising a train carried magnet valve, means for applying the brakes on the train when the winding of said valve is deenergized, a first contact closed only under proceed traffic conditions, for at times controlling said winding, a second contact closed only under caution traffic conditions, and manually operable means for at times shifting the control of said winding to said second contact. 80
13. Railway traffic controlling apparatus comprising a train carried magnet valve, means for applying the brakes on the train when the winding of said valve is deenergized, a first contact closed only under proceed traffic conditions, a second contact closed only under caution traffic conditions, a manually operable device, a first circuit for said winding controlled by said first contact, and a second circuit for said winding controlled by said manually operable device and by said second contact. 85
- In testimony whereof I affix my signature. 105

HERBERT A. WALLACE.
